US00D470904S

(12) United States Design Patent (10) Patent No.: US D470,904 S
(45) Date of Patent: * Feb. 25, 2003

(54) PUTTER HEAD

(75) Inventors: Larry G. Tang, Carlsbad, CA (US);
Joshua G. Breier, Vista, CA (US)

(73) Assignee: Callaway Golf Company, Carlsbad,
CA (US)

() Term: 14 Years

(21) Appl. No.: 29/158,029

(22) Filed: Mar. 27, 2002

(51) LOC (7) Cl. 21-02

(52) U.S. Cl. D21/742

(58) Field of Search D21/736-746;
473/251-256, 324, 327, 328, 340, 341

Primary Examiner—Mitchell Siegel

(74) Attorney, Agent, or Firm—Michael A. Catania

(57) CLAIM

The ornamental design for a putter head, as shown and described.

DESCRIPTION

FIG. 1 is a top perspective view of a putter head thereof;
FIG. 2 is a top plan view of a putter head thereof;
FIG. 3 is a bottom plan view thereof;
FIG. 4 is a front view thereof;
FIG. 5 is a back view thereof;
FIG. 6 is a right side view thereof; and,
FIG. 7 is a left side view thereof.

The broken line showing is for illustrative purposes only and forms no part of the claimed design.
